INVENTOR

UNITED STATES PATENT OFFICE.

GUY BENNETT WAITE, OF HOBOKEN, NEW JERSEY.

CONCRETE ARCH.

SPECIFICATION forming part of Letters Patent No. 721,982, dated March 3, 1903.

Application filed April 19, 1902. Serial No. 103,766. (No model.)

To all whom it may concern:

Be it known that I, GUY BENNETT WAITE, a citizen of the United States, residing at Hoboken, New Jersey, have invented certain 5 new and useful Improvements in Fireproof Floor-Arches, of which the following is a specification.

My invention relates to improvements in the construction of concrete floor-arches having steel members as a component part of the construction.

I have discovered that small light thin steel channels entirely embedded in the concrete below the neutral axis, with the whole construction resting upon and solidly built between rigid supports, take sufficient hold on the concrete to not only make the steel act as a tension member after the concrete is thoroughly hardened, but such steel sections are 20 of great service in holding up the concrete when the latter is only partially hardened.

A fireproof floor construction embodying my invention in several forms is illustrated in the accompanying drawings, wherein—

25 Figure 1 is a top view showing floor-beams and steel arch-channels running at right angles to them. Fig. 2 is a longitudinal sectional view of the construction shown in Fig. 1 and showing the channels as run over the tops of the floor-beams and dropped down into the concrete between said floor-beams. Fig. 3 is a similar sectional view on the line A A of Fig. 1, illustrating a construction wherein the channels are hung in suspender 30 from the tops of the floor-beams. Fig. 4 is a sectional view of a concrete-arch construction where the concrete and the steel channels rest on top of the lower flanges of the floor-beams. Fig. 5 is a cross-sectional view 35 of the construction shown in Fig. 2. Fig. 6 is a cross-sectional view of the construction shown in Fig. 3. Fig. 7 is an enlarged cross-sectional view of the construction shown in Fig. 4, and Figs. 8 and 9 are detail views 40 showing the suspenders for holding the steel channels in position for the construction illustrated in Figs. 3 and 6.

Referring to the drawings, the letter I designates ordinary steel girders or floor-beams 45 of the usual I-beam pattern for supporting the floor-arches.

C designates the concrete filling extending

between adjacent floor-beams. In this concrete filling I embed at suitable intervals a series of light thin steel channels, these channels lying in a direction at right angles to the floor-beams and longitudinally of the concrete arches formed between the floor-beams, and one salient, valuable, and novel feature of my invention resides in making these channels low or thin in vertical dimensions relatively to the total thickness or height of the concrete filling, so that the channels do not have the effect of widely separating the volumes lying between them and cutting the arch up into slices, as it were, as has heretofore been done in the case of insertions of height a nearly equal to the thickness of the concrete itself. Another novel and valuable feature of my invention resides in the location of these channels in the tension zone of the arch, whereby they become and act as tension members of a truss and of which the superposed body of concrete constitutes the compression member, and being 55 so located to serve as tension members purely they can obviously be made of very light and thin steel consistently with their highest efficiency for their intended purpose. While it is of the essence of my invention that these 60 steel reinforcing-channels be located relatively to the body of concrete, as before described, yet it is obvious that for the purposes of construction they may be supported in a variety of ways during the filling in of the 65 concrete therearound. For instance, in Figs. 2 and 5 I have shown them as run over the tops of the floor-beams and dropped down into the concrete. In Figs. 3 and 6 I have shown them as suspended in position by 70 means of wire suspenders E, hung over the tops of the floor-beams and carrying the ends of the channels. In Figs. 4 and 7 I have shown the channels as resting at their ends upon the lower flanges of the floor-beams. 75 In all of these constructions it will be understood that the means shown for supporting the channels are not intended to constitute any part of the strength-giving element or 80 feature of the floor construction, but are merely designed to hold the channels in proper position, as it were, during the filling in of the concrete, both the concrete filling 85 and the channels finding their ultimate real 90 95 100

support on the lower flanges of the floor-beams constituting the base-supports of the arch. It will be understood that in the case of the construction illustrated in Figs. 4 and 7 the 5 concrete "flat" arch C, with the embedded channels, is as much a floor construction as either of the constructions shown in Figs. 2 and 3, since any suitable filler will be interposed above the concrete up to the level of 10 the tops of the floor-beams.

When the entire construction is built on top of supports and is tightly embedded between rigid abutments, the construction has three distinct elements of strength—first, the 15 strength of the channels, stiffened with the concrete engaged about it, acting as an independent beam; second, the concrete (strengthened with the channels) wedged in between abutments acts like a real arch, the upper 20 part of the concrete being the crown of the arch; third, the concrete and the steel channels acting together as an independent beam, the concrete taking the compressive stresses and the channels taking the tensile stresses 25 of the steel concrete beam.

I have found that the channel section where not high enough to weaken the concrete by cutting it into sections is capable of acting with the concrete in the various ways above 30 mentioned, and the combination when used in the manner described is capable of forming arches of phenomenal strength. It will be seen that a load placed midway between the beams tends to deflect the mass downward. This not only puts the channels in 35 tension, but also tends to similarly deflect the channels. To resist such deflection, the channel form is greatly superior to a round rod or wire or a flat bar of equal cross-sectional area, 40 so that the channel, supported at its ends by the flanges of the floor-beam through the vertical legs of the concrete, lends a valuable direct resistance to vertical deflection as well as a tensile resistance in the concrete mass. 45 I am aware that it is old to embed steel beams, rods, wire-netting, and the like in the

concrete or cement of floor and ceiling constructions, and I make no claim, broadly, to the use of such steel reinforcing devices; but, so far as I am aware, such steel beams as 50 hitherto employed have been so located as to virtually cut the concrete vertically into slices or sections, and thus produce an element of weakness in the construction greater than their supposed reinforcing effect, while wires, 55 netting, and the like similarly embedded have been found unsatisfactory by reason of their tendency to stretch and yield. Both of these difficulties I believe I have overcome through the employment of comparatively light low 60 thin steel channel-beams wholly embedded in the concrete mass and located below the neutral axis and within the tension zone of the arch, and, so far as I am aware, I am the first to employ such reinforcing devices in 65 such a relation to the concrete mass.

I claim—

1. In a concrete-floor support the combination with the concrete, of small light steel channels wholly embedded in the lower zone 70 thereof to reinforce the tensile resistance in said zone.

2. In a concrete-floor support, the combination with the horizontal concrete mass of small light steel channels wholly embedded in the 75 tension region of said mass, the whole supported upon the lower flanges of the beams.

3. The combination with small light steel channels supported during construction by suspension from the top of the beams, of a 80 horizontal concrete mass cast upon and about said channels and embedding them wholly in its tensional portion, and, adjacent to the beams, extended downward to the lower flanges thereof.

Signed at the city of New York, in the county of New York and State of New York, this 18th day of April, A. D. 1902.

GUY BENNETT WAITE.
